UNITED STATES PATENT OFFICE.

FRANK J. KRISTOFEK, OF ST. PAUL, MINNESOTA, ASSIGNOR TO BROWN & BIGELOW,
OF ST. PAUL, MINNESOTA, A CORPORATION OF MINNESOTA.

DESK-PAD AND CALENDAR-HOLDER.

1,347,225.

Specification of Letters Patent. Patented July 20, 1920.

Application filed May 17, 1917. Serial No. 169,353.

To all whom it may concern:

Be it known that I, FRANK J. KRISTOFEK, a citizen of the United States, residing at St. Paul, in the county of Ramsey and State of Minnesota, have invented a new and useful Improvement in Desk-Pad and Calendar-Holders, of which the following is a specification.

My invention has for its object the production of a desk pad and calendar holder designed to be used to conveniently hold a calendar in connection with a scratch or memorandum pad.

The primary object is in providing a device formed of thin sheet material which does not require felt or other padding on the under-side of the same to prevent scratching the desk or article it is placed upon, still having an attractive design.

It is also an object to have a pencil or pen holding groove formed in the upper portion of the device, the groove being formed by one of the supports.

Another object is in holding the scratch pad against longitudinal or transverse motion and thereby preventing easy displacement of the pad. It is an object to hinge the calendar holding means to the upper portion of the pad holder so that when it is desired, it can be folded over the upper portion of the scratch pad to give a compact device.

In the drawing forming part of this specification:—

Figure 1 is a perspective of the desk pad and calendar holder.

Fig. 2 is a side elevation.

Fig. 3 illustrates a plan of an alternative construction.

Fig. 4 is a perspective of a detailed portion used in the alternative form as illustrated in Fig. 3.

In the drawing, A represents a scratch pad holder with a calendar holding means B hinged to the same by means of the hinge 1. The pad holding means A is formed of a single piece of thin sheet material 2, having a flat upper surface 3 with downwardly projecting longitudinal flanges 4 on either side.

The flanges 4 form a stiffening means for the upper flat surface 3 upon which the scratch pad C rests.

The scratch pad C is of ordinary construction having a series of sheets 5 bound together at the top by means of the staples

6 or any other suitable means and having a cardboard backing 7 along the under-side of the pad. The pad C is held rigidly to the holder A on the surface 3 by means of engaging tongues or members 8 which are formed by bending up a portion of the sheet material 2 to extend at right angles to the surface 3 and with end portions lying parallel to the surface 3. The members 8 engage the upper corners of the pad C. A vertical stop 9 is stamped out of the surface 3 and is bent to extend at right angles to the surface 3 so as to engage or form a stop for the upper end of the pad C. The stop 9 is centrally disposed between the sides of the holder A.

An engaging lug or tongue 10 is formed near the bottom of the holder so as to engage the backing 7 centrally to prevent the pad C from sliding longitudinally or transversely out of the engaging tongues 8, thus the engaging tongues 8, stop 9 and tongue 10 hold the pad C rigidly on the surface 3 of the holder A against easy displacement transversely or longitudinally of the holder. The sheets 5 of the pad C are perforated on the line 11 so they can be torn off when desired to expose a new sheet 5.

The sheet 2 is extended downwardly from the surface 3 at the bottom of the holder A so as to form a transverse support 12 for the lower end of the holder with a cylindrical lower surface 13, extending across the width of the holder A. At the upper end of the holder A, the sheet 2 is bent downward to form a transverse support 14 for the upper end of the pad C. The support 14 has an outer cylindrical surface 15 and an upwardly projecting forward end 16. The upwardly projecting portion 16 is formed with a hinge portion which makes up part of the hinge 1 to hold the calendar holder B pivotally to the end 16.

The support 14 is semi-cylindrical in shape and extends transversely across the upper end of the holder A and the lower cylindrical surface 15 forms a smooth bearing surface for the upper end of the holder A. Thus when the holder is placed on a desk or other piece of furniture with a highly polished surface, the supports 12 and 14 will prevent the holder A from scratching the surface.

The support 14 is formed so as to hold

the upper end of the holder A above the lower end having the support 12, thus the pad C is held on an angle to the surface on which the holder A is placed and the flanges 4 formed on the side of the holder are greater in depth at the upper end than at the lower end but are formed so as not to extend below the lower surfaces 13 and 15 of the supports 12 and 14. As the supports 10 12 and 14 extend below the lower edges of the flanges 4, they prevent the flanges 4 from engaging the surface of a desk or other article on which the holder A is placed in use, thereby preventing the scratching by the 15 flanges 4.

The calendar holder B is formed with side grooves 18 together with the stops 19 which hold the monthly cards 20 of the calendar in position in the holder B. The 20 back of the holder B extends upwardly to form a portion 21 above the calendar which is of any suitable form or shape to receive suitable display matter. The back of the holder B extends downward at the bottom 25 of the holder B to form a stop 22 projecting centrally from the hinge 1 which engages against the upper end 16 of the support 14 when the holder B is in open position as is illustrated in Fig. 1 and in dotted outline in Fig. 2. When it is desired, the holder B can be turned down or folded over the upper portion of the pad C as is illustrated in Fig. 2, thus forming a compact device. When the calendar holder B is turned 30 down as illustrated in Fig. 2, it will lie practically parallel with the pad C having the calendar face adjacent the pad C. In use, when the calendar holder B is in the position illustrated in Fig. 1 or dotted outline in Fig. 2, the stop 22 engages against the upper end 16 of the support 14 limiting the movement of the holder B on the hinge 1 so that the holder B will extend at an obtuse angle to the side 16.

45 The longitudinal flanges 4 act as trusses for the surface 3 on which the pad C is held and tend to stiffen the surface 3 so that it will be firm and rigid between the supports 12 and 14.

50 The support 14 is so shaped that its inner surface forms a semi-cylindrical groove 24 for a pencil or pen holder at the top of the pad holder A. With this construction, the support 14 performs a double purpose without the use of extra material and gives a desirable shape to the holder.

In the alternative construction illustrated in Figs. 3 and 4, the engaging tongues 8 are formed on a separate member 25 and 55 the holder A is cut away on either side at 26 so as to receive the member 25. The ears 8 on the member 25 are bent into shape after the member 25 has been placed in position on the cut-out portions 26 of the holder A. The forward ends of the flanges

4 and the side of the support 14 form a recess so as to allow the member 25 to lie adjacent the undersurface of the holder A when the pad C is inserted under the ears 8. When the pad C is removed, the member 25 will be held against disengagement from the holder A by means of the engaging ends of the tongues 8 but held loosely or freely thereon. In use of the member 25 for holding the upper sides of the pad C, it is necessary to press the member 25 upward against the undersurface of the holder A so as to raise the ears from the surface 3 sufficiently to allow the upper corners of the pad C to enter therein. It is 80 preferred to have the ears or holding members 8 snugly engage the upper corners of the pad C.

In use of the holder A, the pad C is held tightly against the stop 9 by means of the 85 back engaging tongue 10 and the engaging members 8 prevent the upper portion of the pad from moving transversely on the holder A. The tongue 10 prevents the lower end of the pad C from moving transversely, thus 90 the pad is held in a convenient manner against longitudinal or transverse movement and when all of the sheets 5 of the pad C have been used, the backing 7 secured to the stub 28 can be easily removed by disengaging the lower end of the backing 7 from the tongue whereupon the upper end of the pad C will slip out of engagement with the members 8 and the stop 9.

The calendar holder B is formed with a 100 spring 30 to prevent the calendar cards 20 from sliding out of the grooves 18 by accident. The spring 30 is formed by cutting parallel slots 31 in the back 29 of the calendar holder B. The slots 31 extending parallel and adjacent the grooves 18. The engaging means 30 is bent or curved upward from the surface of the back 29 and engages against the back of the calendar pads 20 when they are inserted in the grooves 18 to 110 press them forward or hold them from slipping easily or accidentally out of the grooves 18.

Having described my invention and illustrated one particular form of construction, 115 I desire to have it understood that I do not wish to confine myself to the particular construction illustrated, but my invention can be carried out by different means and applied to uses other than those above set forth 120 within the scope of the following claims:—

1. In a device of the class described, including a holding means integrally formed from a single piece of thin sheet material adapted to hold a scratch pad against transverse or longitudinal movement, supporting means integrally formed on the bottom of said holding means having smooth cylindrical bearing surfaces and a calendar holder pivoted to said holding means. 130

2. A desk pad and calendar holder, comprising a scratch pad holding means formed from a single piece of material, transverse cylindrical supports at the upper and lower 5 end of said holder, a pencil holding groove formed in said upper support and a calendar-holding means pivoted to said upper support.
3. A device of the class described, comprising a body plate, transverse upper and lower supports formed integral with said body plate, a semi-cylindrical groove formed in said upper support, engaging tongues formed on said body plate for holding the 10 upper corners of said pad, a stop adapted to engage the upper edge of said pad centrally and an engaging tongue formed in the bottom of said holding means for engaging the backing of said pad centrally, whereby said 15 pad is held against transverse and longitudinal movement.
4. A device of the class described, comprising a body portion formed of thin sheet material, supporting means extending transversely of either end of said body portion, 20
5. A desk pad holding means, comprising 30 a flat body portion formed of thin sheet material, supporting means formed integral with and extending transversely to each end of said body portion, one of said supports being higher than the other of said supports, 35 stiffening flanges formed integral with and extending longitudinally of said body portion between said supports, said stiffening flanges being wider on one end than at the other, means for holding a scratch pad on 40 the upper face of said body portion, means for holding a pencil at one end of said body portion, and a calendar holder pivotally secured to one of said supports.

FRANK J. KRISTOFEK.
